UNITED STATES PATENT OFFICE.

GEORGE S. THOMPSON, OF HOCKESSIN, DELAWARE.

STAY-BOLT.

SPECIFICATION forming part of Letters Patent No. 792,863, dated June 20, 1905.

Application filed February 15, 1905. Serial No. 245,646.

To all whom it may concern:

Be it known that I, GEORGE S. THOMPSON, a citizen of the United States, residing at Hockessin, county of Newcastle, and State of Delaware, have invented certain new and useful Improvements in Stay-Bolts, of which the following is a specification sufficient to enable others skilled in the art to which the invention appertains to make and use the same.

5 10 My improvements relate to the form and method of construction of stay-bolts for use in steam-generators, particularly in locomotives, between the outside shell and fire-box shell thereof, and is of the class wherein each bolt is composed of two parts flexibly connected in such manner as to allow a certain degree of longitudinal movement upon and with relation to each other, while incapable of independent rotation upon their longitudinal 15 axes.

15 The invention is designed to afford a maximum of strength for a given size and thickness of bolt and to prolong its life and usefulness by relieving the weaker parts of all 20 danger of excessive pressure by distributing and neutralizing the tension or strain on the parts generally both during manufacture and use. It is also designed to preserve the flexibility of the stay-bolt by preventing the accumulation or lodgment of sediment between the flexible part of the bolt and the surface opposed thereto, the packing and solidifying of sediment between the parts of flexible 25 stay-bolts having been demonstrated to be a 30 source of danger in that it renders the bolt rigid and liable to fracture from lateral strain, particularly at the point of junction with the plate or shell.

In the accompanying drawings, Figure 1 is 35 an elevation of my improved stay-bolt secured to, say, a boiler-plate and a fire-box plate. Fig. 2 is a longitudinal section of the stay-bolt before application to the plates, the section being taken upon plane of line 22, 40 Fig. 1. Fig. 3 is a longitudinal section of the bolt, taken upon plane of line 33, Fig. 2. Fig. 4 is an elevation of the several parts of which the bolt is composed assembled in position with relation to each other. Fig. 5 is 45 50 a transverse section taken upon plane of line

55 Fig. 4. Fig. 6 is a view similar to Fig. 4, illustrating the flattening of the side members of the eye-strap; Fig. 7, a transverse section upon plane of line 77, Fig. 6. Fig. 8 is a side view of the fillet, and Fig. 9 an 55 elevation of the inner end of the same.

55 My improved bolt as a whole is formed, essentially, of an eye-head A in one place and a strap s and filler f, united integrally to form the eye-bolt B.

60 The eye-head A is preferably made of malleable cast-steel or drop-forged steel formed with a slightly-tapering or conical body or shank a, which when finished is threaded externally and peripherally, as shown in the 65 first three figures of the drawings, the rear or outer face or side of the head forming the base of the conic frustum, and hence being the portion of greatest diameter. The body or shank a is also preferably formed with an 70 internal recess a', the side walls of which are formed with plain surfaces a'', arranged at an angle with relation to each other, so as to afford a hold or purchase for the end of a suitable driving implement. Any plural-sided or 75 polygonal form of internal recess a' will answer, and thereby obviate the need of external shoulders for this purpose, thus insuring a practically flush surface with the outside of the sheet c, which is usually the boiler-shell by preference. This is of importance 80 where the use of asbestos lagging or other covering is desirable, since it obviates the need of cutting holes in the lagging to accommodate the heads of the stay-bolts, which are 85 frequently only four inches apart. It is also an important consideration in locomotives in which the wheels extend in close proximity to the outer shell.

90 The eye a²² of the head A is oblong, having an approximately semicircular seat a³ of a diameter equal to that of the cross-section of the concentric portion of the loop s' of the strap s and an extension a⁴ of greater area to facilitate the insertion of the strap s and 95 also to prevent contact between the strap and the body or shank a of the head during and after the formation of the eyebolt B, as hereinafter set forth.

100 In the formation of the eyebolt B a round

rod of wrought-iron or mild steel of a length equal approximately to twice that of the eye-bolt desired and of a diameter equivalent to the width of the seat a^3 in the eye a^2 of the 5 head A is passed through said eye a^2 and its ends $s'' s''$ bent over parallel to each other and against a central filler f , which is preferably of like metal and the function of which is not only to form a core or body for the eye-bolt, but also to afford a bearing or contact 10 surface of special construction for engagement with the opposed concentric surface a^5 of the eye-head A. The filler f , with its finished inner end f' , is shown in Figs. 8 and 15 9 as shaped preparatory to its incorporation with the ends or side members $s'' s''$ of the strap s to constitute the body of the eyebolt A—that is to say, the end f' is faced with two concave surfaces $f^2 f^2$ of the same radius as that 20 of the opposed concentric surface a^5 of the eye-head A, against which concentric surface a^5 they are destined to rest, the said finished end f' of the filler being also formed with a depressed surface or recess f^3 between the concave surfaces 25 $f^2 f^2$ for the purpose of avoiding central contact with said concentric surface a^5 of the eyebolt. As a result the bow or bridge of the eye a^2 is practically relieved of all pressure or strain exerted by or upon the bolt A in the direction of the eye-head A, since the bearing-surfaces $f^2 f^2$ coincide in position with the sides $a^6 a^6$ of the eye a^2 when the parts are in alinement, said sides $a^6 a^6$ constituting, essentially, the piers of the concentric bridge or bow 30 35 a^5 and being reinforced by the body of the eye-piece, so that during the swaging, heading, or upsetting of the stub end of the finished bolt in securing it to a plate d the strain and impact transmitted to the eye-head A is in the direction of greatest resistance, and the weaker central part of the loop is protected and maintained in shape with its fiber unimpaired. Furthermore, by reason of the elongated form 40 of the eye a^2 with its extension a^4 of greater 45 diameter than its seat a^3 the concentric concave bearing-surfaces $f^2 f^2$ of the filler f by their contact with the concentric portion a^5 of the eye-head A also protect the bow or concentric portion s' of the eyebolt B itself, since 50 they hold said concentric portion s' of the strap s to its seat a^3 and prevent its contact with the opposed inner surface of the eye-head A during the heading or upsetting operation. By thus preserving the integrity of 55 outline of the concentric portion s' of strap s I not only maintain its strength unimpaired, but also prevent the lodgment of sediment between it and the opposed inner surface a^7 of the eye-head A, since the uniformly-curved 60 concentric surface s^2 is less adapted to afford support or lodgment than a battered or irregular surface, the peripheral surface s^2 even when in motion always traveling in the same path and occupying the same position with 65 relation to the opposed stationary surface a^7

of the eye-head A and affording the least possible resistance or obstruction to the flow or passage of sediment between said opposed parts, whereas were the peripheral surface s^2 uneven or flattened it would tend to collect 70 sediment between it and the opposed surface a^7 of the eye-head and to compress and harden such sediment in case of any movement or play of the eyebolt with relation to the eye-head. 75

It will be seen, as before intimated, that the concentric portion s' of the eye of the bolt B is circular in cross-section and of the full diameter of the strap s as originally applied to the filler f , thus affording the maximum degree of strength in the direction of greatest strain—namely, in the longitudinal or axial line of the bolt—since in both form and texture the arch s' practically retains the same structure as that of the rod from which the strap s is made. Thus I design to use for the strap a rod of maximum thickness, affording a loop or eye the semicircular diameter of which (see $x x$, Fig. 5) may equal or even exceed the smaller diameter of the bore or tap c' in the plate c made for the reception of the conical eye-head A, in which latter case obviously the eye of the bolt B could not be passed through said aperture unless reduced in size laterally. Hence I use a strap of relatively large diameter and compress the side members $s'' s''$, adjacent to the eye of the finished bolt B, by any suitable means until the greater diameter ($y y$, Fig. 7) of the eyebolt B is less than that of the smaller diameter of the tapped hole c' in the plate c , so that the said bolt may be introduced through said aperture. This operation not only reduces the size of the bolt-eye externally, but it also sets the fiber of the metal of which this portion of the strap 80 is composed so that resilience and stretch is eliminated, thus insuring an intimate and permanent contact of the concentric bearing-surfaces $f^2 f^2$ of the filler f with the concentric surface a^5 of the eye-head A when the end members $s'' s''$ of the strap s are welded to the filler f , and thereby obviating all looseness or play longitudinally between the head A and bolt B. Practically, however, to all intents and purposes the eyebolt or loop is of 85 a size and strength equivalent to that afforded by the full diameter of the bar or rod of which the strap is made, since the compression of the side members $s'' s''$, while it alters their shape in cross-section from a circular to approximately that of an oval, does not essentially reduce their area in cross-section, the elongation being slight and being taken up and compensated for in the welding of the said side members $s'' s''$ to the filler; hence 90 the avoidance of subsequent "stretch" and the maintenance of the maximum degree of resistance against strain or pressure. This relatively high degree of strength and tenacity in the bolt B is also contributed to largely 95 100 105 110 115 120 125 130

by the continuity of fiber maintained in the strap by forming it of a single piece or rod of metal bent over upon and welded to the filler f , the strap s extending at either extremity to the stub end of the bolt, so as to be included in the upsetting or heading process by which this end of the bolt is secured to the plate d , as illustrated in Fig. 1. Thus the strain or pressure in use is uniformly distributed throughout the bolt, the weld extending on both sides of the filler from eye to stub end and there being no relatively weaker portion, as where an end of a loop drawn out from the body on one side is welded to a small area on the other side of the bolt-body, as heretofore, in which case the strength of the weld represents the available maximum strength of the stay-bolt. After welding and shaping the body of the bolt B its stub end is formed with the screw-thread b for engagement with a thread d' , tapped in the plate d . The bolt B is preferably made longer than actually necessary, so as to facilitate the introduction of the said stub end through the tap c' into the tap d' , the superfluous portion of the stub end being chiseled off after the eye-head has been driven home and preparatory to the upsetting operation.

What I claim as my invention, and desire to secure by Letters Patent, is—

1. A two-part stay-bolt consisting of an eye-head formed with a tapered body portion which is threaded, and an eyebolt, the parts being coupled together by the interlocking of their eye-loops for the purpose described.

2. A two-part stay-bolt consisting of an eye-head formed with a semicircular seat in its eye and with an external surface concentric to said seat, and an eyebolt coupled to said eye-head and formed with bearing-surfaces which engage with said concentric surface on the eye-head, the bolt being recessed centrally between said bearing-surfaces for the purpose set forth.

3. A two-part stay-bolt consisting of an eye-head formed with a semicircular seat in its eye and with an external surface concentric to said

seat, and an eyebolt coupled to said eye-head and formed with bearing-surfaces which engage with said concentric surface on the eye-head, the bolt being recessed centrally between said bearing-surfaces for the purpose set forth. 50

4. A two-part bolt consisting of an eye-head formed with a semicircular seat in its eye with an extension of the eye of larger diameter than the said seat and with an external surface concentric to said seat, and an eyebolt coupled to said eye-head and formed with bearing-surfaces which engage with said concentric surface on the eye-head, the bolt being recessed centrally between said bearing-surfaces for the purpose set forth. 55

5. A two-part stay-bolt consisting of an eye-head and an eyebolt coupled therewith, said eyebolt being formed of a central filler and of a strap welded thereto and extending the full length of the bolt on opposite sides of the filler, for the purpose set forth. 60

6. A two-part stay-bolt consisting of an eye-head and a bolt coupled thereto, said eyebolt being formed of a central filler and of a strap looped into the eye in the said eye-head, and having its ends welded to the filler for the purpose described. 70

7. A two-part stay-bolt consisting of an eye-head and an eyebolt coupled therewith, said eyebolt being formed of a central filler and of a strap welded thereto, the side members of the strap being flattened beyond the bend of the loop or eye for the purpose set forth. 75

8. A two-part stay-bolt consisting of an eye-head formed with a tapered body portion which is threaded, said threaded body having a central recess the side walls of which are adapted to engage with a driving implement, and an eyebolt, the parts being coupled together by the interlocking of their eye-loops for the purpose set forth. 80 85
